United States Patent

Des. 242,394
Patented Nov. 16, 1976

242,394

TRAVELING BAG

Thomas D. Tweedie, Monrovia, Calif., assignor to Samsonite Corporation, Denver, Colo.

Filed Dec. 2, 1974, Ser. No. 528,683

Term of patent 14 years

Int. Cl. D3—01

U.S. Cl. D87—5 G

FIG. 3.

FIG. 4.

FIG. 5.

FIG. 1 is a perspective view of a traveling bag showing my new design.

FIG. 2 is a right end elevational view.

FIG. 3 is a top plan view.

FIG. 4 is a side elevational view.

FIG. 5 is a bottom plan view.

The side opposite that shown in FIG. 4 is identical therewith.

I claim:

The ornamental design for a traveling bag, as shown and described.
